UNITED STATES PATENT OFFICE.

WILLIAM E. HILL, OF KALAMAZOO, MICHIGAN.

LOG-TURNER.

SPECIFICATION forming part of Letters Patent No. 315,032, dated April 7, 1885.

Application filed August 18, 1884. (No model.)

To all whom it may concern:

Be it known that I, WILLIAM E. HILL, a citizen of the United States, residing at Kalamazoo, county of Kalamazoo, State of Michigan, have invented a new and useful Cant-Machine, of which the following is a specification.

This invention has for its object certain improvements in such devices, hereinafter described and claimed.

In the drawings forming a part of this specification, Figure 1 is a side elevation and a sectional view of a mill-floor, and Fig. 2 is an elevation looking from a point at the right hand of Fig. 1.

The engine B is pivotally supported at the lower end, the supporting-plate in which the pivot or axis has its bearing being provided with an opening beneath the engine to allow the latter to tilt on its pivot.

A is the mill-floor above the engine B, on which are located the roller-platforms P D a.

The device as here shown is used to throw slabs, logs, boards, or scantling, or cants, &c., from the rollers a a onto the rollers D, which latter-named rollers convey it to the rollers P. The rollers P convey it to other locations in the mill—as, for instance, if sawed lumber n previous to edging, the rollers P convey the same to an edging-saw. One or more of the pivoted cant-levers f may be used. In Fig. 2 a number are shown.

E is a rocking shaft provided with arms v v, one or more, according to the number of cant-levers f used. The rocking shaft E is provided with an arm, v', which is pivotally connected with the piston y of the engine B. The cant-levers f are connected with the arms v v of the shaft E by means of bars e, pivotally connected with said arms and levers.

In the operation, when the piston y rises, the rocking shaft turns, raising the cant-levers f to the position shown in dotted lines in Fig. 1. In this figure the lever f has raised a slab, n', in the act of landing it onto the rollers D.

In Fig. 2 an automatic throttle-lever, e, is shown. In this connection the rollers a a represent a transfer mechanism propelled by machinery. (Not here shown.) In some mills an endless-chain carriage is used in lieu of the rollers a a. The automatic throttle-lever e may be used with, and means of, transferring or moving lumber in the relation here shown.

The lever e is centrally pivoted to a bell-crank, y', and the lower end is connected with the throttle of the engine by means of rods t u and a bell-crank, d. The upper end of the lever e is extended above the upper plane of the transfer a a. By this means, when moving lumber n comes in contact with the lever e, the throttle is automatically opened and the cant-levers set in operation to throw the lumber onto other transfer devices, carriages, or skidways, as the case may be, or, in the absence of any of these, to throw the lumber into a pile onto the floor.

A lever, r, is connected with one arm of the bell-crank y' by means of a rod, S, by which means the throttle-lever e may be thrown down to allow the lumber to pass on when not desiring to use the cant-levers.

Having thus described my invention, what I claim as new, and desire to secure by Letters Patent, is—

1. In a cant-machine, the combination of the rock-shaft provided with an arm for pivotal connection with the engine piston and with arms for connection with the cant-levers, cant-levers pivoted at one end, and bars pivotally connecting the arms of the rock-shaft with the free ends of the cant-levers, substantially as set forth.

2. The combination of the engine, cant lever or levers, a suitable lumber-transfer device, and a centrally-pivoted throttle-lever having one end extended beyond the plane of the transfer device and the other end pivotally connected by suitable means with the engine-throttle, for the object stated, all substantially as set forth.

3. The combination of the engine, cant lever or levers, a suitable lumber-transfer device, a throttle-lever centrally pivoted to a bell-crank and having one end extended beyond the plane of the transfer device, suitable means pivotally connecting the other end with the engine-throttle, a pivoted hand-lever, and a rod pivotally connecting said hand-lever and bell-crank, all substantially as set forth.

In testimony of the foregoing I have hereunto subscribed my name in the presence of two witnesses.

WILLIAM E. HILL.
